(57) **CLAIM**

The ornamental design for a docking station, as shown and described.

DESCRIPTION

FIG. 1 is a top, front, right-side perspective view of a docking station;

FIG. 2 is a bottom, back, right-side perspective view thereof;

FIG. 3 is a left-side view thereof;

FIG. 4 is a right-side view thereof;

FIG. 5 is a front view thereof;

FIG. 6 is a back view thereof;

FIG. 7 is a top view thereof;

FIG. 8 is a bottom view thereof; and,

FIG. 9 is an enlarged view of an area marked FIG. 9 in FIG.

7.

The dashed broken lines depict portions of the docking station that form no part of the claimed design. The dot-dashed broken lines in FIGS. 7 and 9 represent the enlarged area shown in FIG. 9 and these lines forms no part of the claimed design.

1 Claim, 9 Drawing Sheets
